US0D1060407S

(12) **United States Design Patent** (10) **Patent No.:** **US D1,060,407 S**
(45) **Date of Patent:** **** Feb. 4, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventor: **Nicholas D. Felton**, Sunnyvale, CA (US)

(73) Assignee: **Apple Inc.**, Cupertino, CA (US)

(**) Term: **15 Years**

(21) Appl. No.: **29/930,514**

(22) Filed: **Feb. 29, 2024**

Related U.S. Application Data

(63) Continuation of application No. 29/878,755, filed on Jun. 27, 2023, now Pat. No. Des. 1,035,690, which is a continuation of application No. 29/787,176, filed on Jun. 4, 2021, now Pat. No. Des. 994,683.

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

(Continued)

The broken lines in the figures show a display screen or portion thereof, and form no part of the claimed design.
